UNITED STATES PATENT OFFICE.

WILLIAM J. HALL AND CYRUS FIELD WILLARD, OF SAN DIEGO, CALIFORNIA.

PARACHUTE FOR AEROPLANES.

Application filed October 2, 1926. Serial No. 139,163.

Our invention relates to improvements in parachutes for aeroplanes where the parachute is attached to an aeroplane to prevent it from crashing and being dashed to pieces when striking the ground, after falling some distance, by the parachute, when released, allowing the aeroplane to descend gently until it reaches the earth.

The objects of our invention are:—First, to support the weight of the aeroplane when falling by using two parachutes, one at each end of the wing of the aeroplane to hold it on a level parallel to the earth:—Second, to prevent tail-spins, nose-dives and side-slips when desired:—Third, to help the aeroplane to coast gently to earth when the engine goes dead for any reason:—Fourth, to provide means for releasing and ejecting forcibly and simultaneously the parachute on each end of the aeroplane when it is desired to hold aeroplane level and to prevent the spilling of human beings and valuable freight from the aeroplane:—Fifth, to provide means for quickly storing away the parachutes in suitable receptacles or chambers from which the parachutes may be discharged:—Sixth, to provide means by which the pilot may, at will, discharge or eject the parachutes forcibly and simultaneously up into the air free from the chambers containing them, so they may unfold to support the aeroplane and permit it to descend gently to the earth and Seventh, in general to make commercial aviation, safe, successful and profitable.

We obtain these objects by the mechanism illustrated in the accompanying drawings in which

Fig. 1 is a perspective view of the aeroplane with the parachutes in their receptacles or chambers ready to be discharged by the pilot pulling down the lever shown.

Fig. 2 is a perspective view of the aeroplane with two parachutes functioning after having been discharged into the air by the coil-spring in chamber.

Fig. 3 represents a detailed view in partial section showing the chamber, coil-spring in chamber, and releasing device.

Fig. 4 gives a detailed plan view of the platform on which the parachute rests and which platform is shot up against the rim of the chamber by the coil-spring under platform when the dogs are released from the studs on the edge of platform.

Fig. 5 is a detailed view of dog which holds platform down against force of coil-spring.

Similar numerals refer to similar parts throughout the several views.

1 is the top of the wing of the aeroplane to which the chambers 2—2 are securely fastened at any desired angle, which chambers are round by preference but might be of other shape. In each of these chambers 2—2 is a platform 3 to which are attached three studs 4, which slide up and down in the three slots 5, cut in the side of the chambers the desired length. The rim 6 around the top of the chamber 2 on the outside serves as a stop and prevents the platform 3 from leaving the chamber 2, as the studs 4 strike against the rim 6 at the top of the slots 5 and are held from going any further.

7 is a strong coil-spring underneath the platform 3, which spring is held down by this platform 3 when the studs 4 on the platform 3 are engaged by the peculiar-shaped dog or catch 8, which thus holds the platform 3 down against the force of the coil-spring 7 pushing against the platform 3. 9 is the spring which holds the dog 8 in place over the stud 4, while 10 is the band fitting around the chamber 2 and to which band the dog 8 is attached. This band 10 is semi-circular in shape fitting loosely around the chamber 2 and has attached, to its other end, another dog 8 of the same shape and in the same way as that shown in Figs. 3 and 4. To this band 10 is attached, half-way between its two ends, a bar 11 projecting outwardly from band 10 and at the outer end of bar 11 is the flexible bar-spring 12 which projects downward and is attached to the bottom of the chamber on its outside which is designed to force, through bar 11, the semicircular band 10 against the side of the round chamber 2 and to reinforce the action of the spring 9 to hold the dogs 8 in place over the studs 4.

To the bar 11, near its junction with the bar-spring 12, is attached the rope 13 which passes over pulleys 14 until it reaches the lever 15, which is pivoted on the support or standard 16 fastened securely to the top 1 and projecting downward from the top 1, in such a manner over the pilot in the fuselage, as to permit the pilot to reach up easily and grasp the handle of the lever 15 which controls the operation of the release mechanism.

Reference has been made to the peculiar shape of the dog 8 and it is shown in Figs. 3 and 5 as being made with an inclined plane 17 on its top which is so designed as to permit the studs 4 (when the platform 3 is being

forced down) to slide down on the inclined plane 17 forcing the dog 8 back until the end of the dog is reached when the stud 4 passes by the end of the dog 8, whereupon the pressure of the flexible bar-spring 12 and the pull of the spring 9 draws the dog 8 over the stud 4 and holds it securely and firmly in place.

18 is the rope, of equal length on each of the parachutes, attached to the end of the wing and which rope 18 is firmly connected with the eye-bolt 19 secured to the top 1, and in the other end of the rope 18 is the eye 20 to which are attached the cords 21 of equal length for the parachutes on each end, and these cords are attached in the customary manner to the parachutes 22 at each end of the wing 1.

While we prefer to use ropes 13 to pull back the semicircular bands 10 fitting loosely around each chamber 2, in order to pull back the dogs 8 which hold down the platforms 3, yet it is apparent that other means might be used in place of the ropes so as to perform the same service, such as rods or by electrical means, and so such means are to be considered as covered by this patent.

It is evident that when the pilot of the aeroplane reaches up and grasps the lever 15 and pulls down on the handle of it, as it is pivoted to standard 16, that the lever 15 pulls downward the ropes 13 which pulls back the bars 11 and semicircular bands 10 away from the side of the chamber 2. Band 10 is connected at the back of the dog 8 in such a manner that when the band 10 is pulled backward and downward by the rope 13, the inner end of the dog 8 is lifted and the dog 8 slides backward from its engagement over stud 4 attached to the platform 3. Immediately the end of the dog 8 passes from contact with stud 4, the force of the coil-spring 7 comes into action and the platforms 3 are impelled or catapulted upward with great force. These platforms 3, on which the parachutes 22 lie loosely, compactly packed, being thus catapulted upward, they are suddenly stopped in their movement upward as the studs 4 slide in the slots 5 and strike with great force against the rim 6 which runs all around the chamber 2 to form a top to the slots 5. This sudden impact and stop causes the parachutes 22, which are lying loosely on the platforms 3—3 to be ejected from the chambers 2—2 like projectiles thrown from a gun. These parachutes 22—22, being attached to the rope 18—18 of equal length are thrown clear of the aeroplane by the chambers 2—2 being inclined at an angle to the plane of the top 1, and the parachutes 22—22 are opened by and pull against the ascending columns of air, if the aeroplane is falling, spinning or sliding.

The parachutes 22—22 being attached to the ropes 18—18 of equal length, flexibility is

thus given to them while at the same time they are simultaneously catapulted into the air and opened at the same time, stability is quickly given to the aeroplane.

The diameter of each parachute 22 when opened and the length of the cords 21 should be such as to prevent them from fouling one another when opened and in use.

It is possible to use one or more additional parachutes on the front and rear of the wing, in addition to those shown, by using ropes like 18 of varying lengths, so as to have the parachutes float at different altitudes in order not to foul those at each end of the wing. These additional parachutes may be connected with the lever 15 in such a manner as to discharge at the same time as those on each end of the wing. Having longer ropes 18 and the plane falling, they will open at an altitude higher than those on each end of the wing and thus be out of their way. They may be located on the front of the wing over the engine where the heaviest weight is and also in the rear. They may be timed to discharge sooner or later than those on the ends of the wing, or they may be shot out at the same time, if the pilot so desires, according to the manner in which they are attached to the lever, or they may have an independent lever like 15, as desired, to use only in emergencies.

When the aeroplane has safely landed and it is desired to pack each parachute 22 back in its chamber 2, the platform 3, with the three studs 4, sliding in the three slots 5, is pressed down until two of the studs 4 strike the inclined plane 17 on top of the two dogs 8, which downward pressure forces these dogs 8 back until the two studs 4 on each platform 3 passes beyond the end of the dog 8, whereupon the flexible bar-spring 12 and the spring 9 force the dogs 8 over the studs 4 and the dogs 8 then hold the studs firmly in place, holding down the platform 3 securely against the force of the coil-spring 7, until such time as the platform 3 is again released by the pilot pulling down on lever 15. The parachutes 22 and their cords 21 and the rope 18 are packed away in the chambers 2—2, the parachutes being made of thin waterproof material which may be folded over and over. It may be advisable to have an inner cylinder of pasteboard held to the moving platform 3 until thrown out so as to prevent the folds of the folded parachute, the cords and the ropes from touching against the falls of the chamber 2—2 and causing unnecessary wear and friction.

While a biplane is shown, it is evident that a monoplane, or an aircraft of any kind of construction where parachutes may be deemed necessary, may be used with this invention.

As it might be desired to pack the parachutes back again into their chambers 2 while in flight, after coming out of a tail-spin, nose-dive, or the engine beginning to function nor-

5 mally again, or for any other reason, the the parachutes rest and with studs moving
means for holding the platforms down are in slots in sides of chambers, rims around
so simply made that the platforms can be chambers acting as stops for platforms, 40
easily forced down in their chambers while in
5 flight so that the dogs 8 will hold the studs
4-4 on platforms 3-3 firmly and securely
in place, after which the parachutes can be
hauled in and packed away in the containing
chambers ready for use again. While such
10 action might be dangerous, it is possible.

We are aware that prior to our invention a
parachute has been used attached to an aero-
plane to prevent it crashing to the ground.
We therefore do not claim such a combination
15 broadly but we believe that we are the first
to use two parachutes, one at each end of
wing, to give stability to the aeroplane at all
times and to simultaneously and forcibly eject
from their chambers both parachutes, or all
20 that may be used, by one act of pilot sim-
ultaneously releasing all parachutes that may
be used.

What we claim as new and desire to secure
by Letters Patent, is:

- 25 1. The combination of two or more para-
chutes, an aeroplane, a movable platform on
the edge of which are studs moving up and
down in slots in sides of chambers, rims
30 around chambers to act as stops for studs,
strong coil-springs under the movable plat-
forms to forcibly throw up platforms when
dogs are released and the dogs engaging over
the studs to hold platform down against the
35 force of the coil-springs.
2. The combination of two or more para-
chutes, an aeroplane, chambers attached to
top of aeroplane, movable platforms on which
- the parachutes rest and with studs moving
in slots in sides of chambers, rims around
chambers acting as stops for platforms, 40
strong coil-springs underneath platforms,
dogs held in place over studs by springs, band
attached to two dogs and ropes attached
to bars fastened to bands to pull back the dogs
from over the studs, pulleys carrying such 45
ropes and a lever and support within easy
reach of pilot so he can reach up and grasp
lever and release all parachutes at once.
3. The combination of two or more para-
chutes, an aeroplane to which the parachutes 50
are attached, chambers arranged on top of
the aeroplane, a movable platform on which
the parachutes rest and provided with studs
moving up and down in slots cut in sides of
chambers a rim around each chamber to act 55
as stop for studs on platform, a strong coil-
spring underneath and attached to platform,
dogs held in place over studs by springs of
peculiar shape with an inclined plane on top
of each dog so that when platform is pressed 60
down the studs thereon will move down in-
clined plane forcing dogs back and letting
studs pass by end of dogs, springs to bring
back dogs into place, after studs have passed
by end of dogs, which dogs hold platform 65
down, ropes attached to bands to which dogs
are attached, and a lever pivoted to a support
near pilot's seat within easy reach to which
lever are attached ropes leading to two or
more parachutes so that two or more para- 70
chutes may be released simultaneously, by
one pull downward by pilot on lever.
